(57) **ABSTRACT**

An operation unit for image forming apparatus is disclosed. The operation unit includes: a bearing portion configured to rotatably support a shaft portion; a restricting portion provided at a position different from that of the bearing portion in an axial direction of the shaft portion, a restricting portion being configured such that when a supporting portion is rotated in a first direction from a first angle toward a second angle, the restricting portion restricts a rotation of the supporting portion in the first direction by abutting a mounting portion at a position where the operation unit forms the second angle; and an abutting portion provided on an opposite side of the restricting portion via the bearing portion in the axial direction, the abutting portion being configured to abut on the shaft portion.

OPERATION UNIT AND IMAGE FORMING APPARATUS

BACKGROUND OF THE INVENTION

Field of the Invention

This invention relates to an operation unit and an image forming apparatus that includes the operation unit.

Description of the Related Art

An image forming apparatus such as a copying machine has an operation unit for a user to switch operations and to make detailed settings in each operation. In an image forming system in which optional devices such as a feeding unit, a conveying unit and a post-processing unit are connected to the image forming apparatus, a user also performs tasks such as setting various these optional devices using the operation unit.

When a large imaging forming system in which multiple optional devices are connected together so that the overall length of the imaging forming system becomes large, a user may perform tasks on the optional devices at a distant position from the image forming system on which the operation unit is provided. When such tasks are performed frequently, it is not efficient for the user to return to the image forming apparatus to operate the operating unit.

In view of this, Japanese Patent Application Laid-Open No. 2010-243977 proposes a system in which an operation unit is installed not only on the image forming apparatus but also on an optional device. In the apparatus disclosed in this document, the operation unit is connected to the image forming apparatus by a cable and is movably provided at a location on the top surface of the image forming apparatus where a user can easily operate it within the range of the cable length.

A display panel (display) of the operation unit described in this document, on which information is displayed, is fixed to a stand. Therefore, the posture of the display panel cannot be changed to an angle with which a user can easily operate the operation unit, which does not show an excellent operability.

The operating unit could be equipped with a retractable stand that allows the angle of the display panel to be changed. However, with this configuration, the stand could be damaged when an overload exceeding a predetermined load is applied to the display panel of the operation unit when the retractable stand is open.

SUMMARY OF THE INVENTION

A representative configuration of the present invention is an operation unit used for operating an image forming apparatus that forms an image on a sheet, the operation unit comprising:

a display that displays information on image formation; and

a supporting portion configured to support the operation unit such that with a display surface of the display forming a first angle with respect to a placement surface on which the operation unit is placed or a second angle that is larger than the first angle, the supporting portion abuts on the placement surface, the supporting portion being provided on the operation unit such that the supporting portion being able to rotate between the first angle and the second angle,

wherein the supporting portion includes:

2

a shaft portion working as a rotational center; and a mounting portion on which the shaft portion is provided such that the shaft portion protrudes from the mounting portion, the mounting portion being configured to be able to be elastically deformed by an overload exceeding a predetermined load,

wherein the operation unit includes:

a bearing portion configured to rotatably support the shaft portion;

a restricting portion provided at a position different from that of the bearing portion in an axial direction of the shaft portion, the restricting portion being configured such that when the supporting portion is rotated in a first direction from the first angle toward the second angle, the restricting portion restricts a rotation of the supporting portion in the first direction by abutting the mounting portion at a position where the display surface forms the second angle with respect to the placement surface; and

an abutting portion provided on an opposite side of the restricting portion via the bearing portion in the axial direction, the abutting portion being configured to abut on the shaft portion, and

wherein when a rotational force in the first direction by the overload is applied to the supporting portion that is restricted to the position where the display surface forms the second angle, the mounting portion is elastically deformed in a direction opposite to a direction in which the shaft portion protrudes in the axial direction to release the abutting between the restricting portion and the mounting portion.

Further features of the present invention will become apparent from the following description of exemplary embodiments with reference to the attached drawings.

BRIEF DESCRIPTION OF THE DRAWINGS

FIG. 1 is a diagram showing a perspective view of an image forming system.

FIG. 2 is a diagram showing a cross-sectional view of the image forming system.

FIG. 3 is a block diagram of the image forming apparatus with an operation unit.

FIGS. 4A and 4B are diagrams showing top views of the image forming system in which the operation unit is arranged.

FIGS. 5A, 5B and 5C are diagrams for describing the operation unit.

FIGS. 6A and 6B are diagrams, each showing a perspective view of the operation unit according to the first embodiment.

FIGS. 7A and 7B are diagrams, each showing a perspective view of the operation unit according to the first embodiment.

FIGS. 8A, 8B and 8C are diagrams, each showing a side view of the operation unit according to the first embodiment.

FIGS. 9A, 9B and 9C are diagrams, each showing a perspective view of the operation unit according to the first embodiment viewed from the bottom side.

FIGS. 10A, 10B and 10C are schematic diagrams, each showing a cross-sectional view of the operation unit according to the first embodiment.

FIGS. 11A, 11B and 11C are diagrams, each showing a partial cross-sectional view of the operation unit according to the first embodiment viewed from the bottom side.

FIGS. 12A, 12B, and 12C are diagrams for describing the operation unit according to the first embodiment.

FIGS. 13A and 13B are diagrams for describing the operation unit according to the first embodiment.

FIGS. 14A and 14B are diagrams for describing the operation unit according to the first embodiment.

FIG. 15 is a diagram showing a perspective view of the operation unit according to the second embodiment viewed from the bottom.

FIGS. 16A, 16B and 16C are diagrams, each showing a side view of the operation unit according to the second embodiment.

FIGS. 17A, 17B and 17C are diagrams, each showing a perspective view of the operation unit according to the third embodiment.

FIGS. 18A and 18B are diagrams, each showing a perspective view of the operation unit according to the fourth embodiment viewed from the bottom.

FIGS. 19A and 19B are diagrams, each showing a perspective view of the operation unit according to the fourth embodiment viewed from the bottom.

FIGS. 20A and 20B are diagrams, each showing a perspective view of the operation unit according to the fifth embodiment.

DESCRIPTION OF THE EMBODIMENTS

Hereinafter, embodiments of the present invention will be exemplarily described in detail with reference to the drawings. The dimensions, materials, shapes, and relative positions of components described in the following embodiments should be appropriately changed according to the configuration of the apparatus to which the present invention is applied and various conditions and are not intended to limit the scope of the present invention only to them.

First Embodiment

The image forming system 1 according to this embodiment will be described with reference to FIGS. 1 to 4. As shown in FIG. 1, the direction toward the front side from the image forming apparatus 2 is defined as the forward direction F, and the direction toward the back side from the image forming apparatus is defined as the backward direction B. The direction from the image forming apparatus 2 toward the left side where the post-processing device 103 is located is defined as the left direction L, and the direction from the image forming apparatus 2 toward the right side where the feeding device 105 is located is defined as the right direction R. The left and right directions defined here are respectively orthogonal to the forward and backward directions. Furthermore, the vertically upward direction perpendicular to the forward and backward directions and the left and right directions defined here is defined as the upward direction U and the vertically downward direction perpendicular to the forward and backward directions and the left and right directions defined here is defined as the downward direction D. The forward direction F, the backward direction B, the right direction R, the left direction L, the upward direction U, and the downward direction D are also shown in FIG. 2, 4 and so on.

(Configuration of Image Forming Apparatus)

As shown in FIG. 1, the image forming system 1 in this embodiment includes the image forming apparatus 2, which is a printer, for example, and the post-processing device 103, which is located adjacent to the left direction L side of the image forming apparatus 2 and may stack a sheet S on which an image has been formed. The top of the image forming apparatus 2 has the top surface 109 that can be used as a

work space. The top surface 109 is wider than the maximum size (for example, A3 size) of the sheet S on which this image forming apparatus 2 can form an image.

A user spreads out a drawing on the top surface 109 to perform drafting and other tasks. Therefore, assuming that the floor on which the image forming system 1 is installed is horizontal, the top surface 109 is also configured to be horizontal. Additionally, the top surface 109 is configured as flat as possible. The area indicated by the reference numeral 1010 in FIG. 4A is an example of a work space. If the image forming system 1 is installed horizontally, the work space 1010 will also be horizontal. This area is a part of the top surface 109 and is therefore a flat surface. The term "flat surface" refers to a surface configured such that grooves and other irregularities are minimized except for connection points between components which are unavoidable due to the configuration of the exterior of the image forming system 1. It is sufficient for the work space 1010 to have a flat-surface area enough to spread out an A3 size paper. The top surface 109 is made from a resin plate, for example, and is understood to be a "flat surface" even if it has some degree of rattling or undulation that is unavoidable in manufacturing. Further, the term "horizontal" as used here does not mean horizontal in the strict mathematical sense, but is a concept that includes horizontal to the extent that it can be regarded as horizontal in practice, that is, substantially horizontal.

In this embodiment, a tandem-type full-color printer is described as an example of an image forming apparatus 2. However, the invention is not limited to the image forming apparatus 2 of the tandem-type, but may be an image forming apparatus of another system. Further the invention is not limited to a full color imaging, but may also be monochrome imaging.

As shown in FIG. 2, the image forming apparatus 2 includes the image forming apparatus main body (hereinafter referred to as apparatus main body) 10. The apparatus main body 10 includes the toner supply unit 20, the sheet feeding portion 30, the image forming portion 40, the sheet conveying portion 50, the sheet discharging portion 60, the electrical unit 70, and the operation unit 80. The sheet S as a recording material is the material on which the toner image is formed. Examples of such sheet S include plain paper, a synthetic resin sheet that is a substitute for plain paper, thick paper, and a sheet for an overhead projector.

The sheet feeding portion 30 is located at the bottom of the apparatus main body 10 and is equipped with the sheet cassette 31 that stacks and accommodates the sheets S and the feeding roller 32 that feeds the sheet S to the image forming portion 40.

The image forming portion 40 has the image forming unit 41, the toner bottle 42, the exposure device 43, the intermediate transfer unit 44, the secondary transfer portion 45 and the fixing device 46 to form an image on the sheet S.

The image forming unit 41 has the four image forming units 41y, 41m, 41c and 41k to form a toner image in four colors: yellow (y), magenta (m), cyan (c) and black (k). Each of these can be detachably attachable to the apparatus main body 10 by a user. For example, the image forming unit 41y has the photosensitive drum 47y that forms a toner image, the electrically charged roller 48y, the developing sleeve 49y, an unshown drum cleaning blade, toner, and so on. Toner is supplied to the image forming unit 41y from the toner bottle 42y filled with toner. The other image forming units 41m, 41c and 41k have the same configuration as that of the image forming unit 41y except for the use of different

toner colors, so a detailed description for the image forming units **41m**, **41c** and **41k** is omitted.

The exposure device **43y** is an exposure portion that exposes the surface of the photosensitive drum **47y** to form an electrostatic latent image on the surface of the photosensitive drum **47y**.

The intermediate transfer unit **44** is located in the downward direction D of the image forming unit **41**. The intermediate transfer unit **44** has a number of rollers such as the drive roller **44a** and primary transfer rollers **44y**, **44m**, **44c** and **44k**, and the intermediate transfer belt **44b** that is wound around these rollers. The primary transfer rollers **44y**, **44m**, **44c** and **44k** are positioned opposite the photosensitive drums **47y**, **47m**, **47c** and **47k**, respectively, and abut on the intermediate transfer belt **44b**. By applying a transfer bias with a positive polarity to the intermediate transfer belt **44b** by the primary transfer rollers **44y**, **44m**, **44c** and **44k**, toner images with negative polarity on the photosensitive drums **47y**, **47m**, **47c** and **47k** are sequentially and multiply transferred on the intermediate transfer belt **44b**. As a result, a full-color image is formed on the intermediate transfer belt **44b**.

The secondary transfer portion **45** has the secondary transfer inner roller **45a** and the secondary transfer outer roller **45b**. By applying a secondary transfer bias with positive polarity to the secondary transfer outer roller **45b**, the full color image formed on the intermediate transfer belt **44b** is transferred to the sheet S. The secondary transfer inner roller **45a** is placed inside the intermediate transfer belt **44b**, and the secondary transfer outer roller **45b** is located opposite the secondary transfer inner roller **45a** via the intermediate transfer belt **44b**.

The fixing device **46** has the fixing roller **46a** and the pressure roller **46b**. The toner image transferred to the sheet S is pressurized and heated to fix the image on the sheet S as the sheet S is held and conveyed between the fixing roller **46a** and the pressure roller **46b**.

The sheet conveying portion **50** has the pre-secondary-transfer conveying path **51**, the pre-fixing conveying path **52**, the discharge path **53** and re-conveying path **54** so that the sheet conveying portion **50** conveys the sheet S fed from the sheet feeding portion **30** from the image forming portion **40** to the sheet discharge portion **60**.

The sheet discharge portion **60** has the discharge roller pair **61** located downstream of the discharge path **53** and the discharge port **62** located on the side of the left direction L of the apparatus main body **10**. The discharge roller pair **61** feeds the sheet S conveyed from the discharge path **53** from the nip portion and discharges it from the discharge port **62**. The discharge port **62** can feed the sheet S to the post-processing device **103** located on the left direction L side of the apparatus main body **10**.

As shown in FIG. 3, the electrical unit **70** has the image controller **71**, which is a control board including the control portion, and the hard disk drive (HDD) **72**, which is a removable large capacity storage device. The image controller **71** is configured with a computer and has for example the CPU **73**, the ROM **74** that stores a program to control each part, the RAM **75** that temporarily stores data, and the input/output circuit (I/F) **76** that inputs and outputs signals to and from the outside. The HDD **72** is a removable large capacity storage device for storing electronic data and stores mainly an image processing program, digital image data and incidental information of digital image data. The image data are read out from the HDD **72** during image forming.

The CPU **73** is a microprocessor that controls the entire image forming apparatus **2** and is the main member of the system controller. The CPU **73** is connected to the sheet feeding portion **30**, the image forming portion **40**, the sheet conveying portion **50**, the sheet discharge portion **60**, the HDD **72**, and the operation unit **80** via the input/output circuit **76** to exchange signals with each portion and control its operation. A user can operate and set the image controller **71** through commands from an unshown computer connected to the apparatus main body **10** or by operating the operation unit **80**.

The operation unit **80** is used for operating the image forming apparatus **2**. The operation unit **80** is provided separately from the apparatus main body **10**. With the operation unit **80**, each portion of the apparatus main body can be operated. The operation unit **80** has the driver board **81** and the display **82** (liquid crystal touch panel). The display **82** is configured to display information (information about image forming) necessary for a user to operate the image forming apparatus **2**, such as the remaining amount of the sheets S and toner replenished in the apparatus main body **10**, a warning message when the consumables run out, and the procedure for replenishing the consumables. The display **82** is configured to accept an operation input from a user such as data for setting the size and basis weight of the sheet S, adjusting the image density, and setting the number of output sheets. The display **82** of the operation unit **80** in this embodiment is a liquid crystal touch panel. Namely, the display **82** is configured to accept touch operation by a user. Touch operation refers to the operation of touching the display **82** with a fingertip, and is the generic term for operations such as flicking and scrolling.

The operation unit **80** can be energized by being connected to the electrical unit **70** of the apparatus main body **10** with the cable **90**. The cable **90** includes the bundle of signal line **90a** and the power line **90b**, but the signal line **90a** and the power line **90b** may be accommodated in separate cables. The signal line **90a** connects the input/output circuit **76** of the image controller **71** with the driver board **81**, and the power line **90b** connects the power supply **12** of the apparatus main body **10** with the driver board **81**.

Next, the image forming operation of the image forming apparatus **2** configured as above will be described using FIG. 2.

When the image forming operation starts, the photosensitive drums **47y**, **47m**, **47c** and **47k** first rotate and their surfaces are charged by the charging rollers **48y**, **48m**, **48c** and **48k**. Then, a laser beam is emitted to the photosensitive drums **47y**, **47m**, **47c** and **47k** by the exposure devices **43y**, **43m**, **43c** and **43k** based on image information so that an electrostatic latent image is formed on the surface of the photosensitive drums **47y**, **47m**, **47c** and **47k**. When toner adheres to this electrostatic latent image, it is developed and visualized as a toner image, and then is transferred to the intermediate transfer belt **44b**.

Meanwhile, in parallel with this toner image forming operation, the feed roller **32** rotates to feed the topmost sheet S in the sheet cassette **31** while separating it from the other sheets. The sheet S is then conveyed to the secondary transfer portion **45** via the pre-secondary-transfer conveying path **51**, in synchronization with the timing of the toner image on the intermediate transfer belt **44b**. Next, the image is transferred from the intermediate transfer belt **44b** to the sheet S and the sheet S is conveyed to the fixing device **46**, where the unfixed toner image is heated and pressurized to fix the image on the surface of the sheet S. Then, the fixed sheet S is discharged from the discharge port **62** by the

discharge roller pair 61 and supplied to the post-processing device 103. The fixed sheet S is discharged from the discharge port 62 by the discharge roller pair 61 and supplied to the post-processing device 103.

(Arrangement of Operation Unit)

First, outlines of the electrical unit 70, the operation unit 80, the cable 90, the cover 101, and the opening 102 will be described using FIGS. 4A and 4B.

The electrical unit 70 is provided on the back surface of the apparatus main body 10. A connector (a connecting portion on the apparatus main body side, not shown) provided at one end of the cable 90 is connected to the electrical unit 70. The cable 90 is configured to communicably connect the apparatus main body 10 with the operation unit 80. The other end of cable 90 is provided with a connector (a connecting portion on the operation unit, not shown) and is connected to the operation unit 80.

Thus, the operation unit 80 is not secured to the top surface 109 of the image forming apparatus 2, although it is connected to the apparatus main body 10 by the cable 90. The operation unit 80 is provided separately from the apparatus main body 10 and is located movable with respect to the top surface 109. Therefore, a user can freely arrange the operation unit 80 at any position on the top surface 109 as long as the cable 90 reaches. Thus, "freely" here means that the operation unit 80 can be placed at any position on the top surface 109 since the operation unit 80 is not secured to the top surface 109 with for example screws or the like.

In this embodiment, the apparatus main body 10 and the operation unit 80 communicate bidirectionally via the cable 90. Therefore, as mentioned above, the operation unit 80 can be freely repositioned within the length of cable 90.

FIGS. 4A and 4B illustrate the positions where the operation unit 80 can be placed on the top surface 109. For example, as shown in FIG. 4A, the operation unit 80 can be placed in the space closer to the document reading device 115 on the top surface of the image forming apparatus 2. Further, as shown in FIG. 4B, the operation unit 80 can be placed in the space on the top surface 106 of the feeding device 105 as well. In addition to the arrangement shown in FIGS. 4A and 4B, the operation unit 80 can be placed on the top surface of the image forming system 1, such as the top surface 104 of the post-processing device 103. In addition to the space on the top surface of the image forming system 1, it is also possible to install a workbench or the like near the image forming system 1 and to place the operation unit 80 on it (not shown).

(Mounting Posture of Cover)

Next, the mounting posture of the cover 101 will be described.

When the operation unit 80 is placed near the document reading device 115 on the top surface 109 of the image forming apparatus 2 and near the front side as shown in FIG. 4A, the cover 101 is mounted in a first mounting posture where the opening 102 on the cover 101 is placed near the front side. The cable 90 connected to the electrical unit 70 by the connector (the connecting portion on the apparatus main body side, not shown) passes under the cover 101 and is connected to the operation unit 80 by the connector (the connecting portion on the operation unit side, not shown) through the opening 102 of the cover 101.

When the operation unit 80 is placed on the top surface 106 of the feeding device 105 as shown in FIG. 4B, the cover 101 is mounted in a second mounting posture where the opening 102 of the cover 101 is placed near the back side of the image forming apparatus 2. The cable 90 connected to the electrical unit 70 by the connector (the connecting

portion on the main apparatus body side, not shown) does not pass under the cover 101 and through the opening 102, but passes through an opening (not shown) on the main apparatus body side of the image forming apparatus 2 and is connected to the operation unit 80 by the connector (the connecting portion on the operation unit side, not shown).

The reason for changing the mounting posture of the cover 101 is to restrict the movement of the cable 90 by the passing of the cable 90 through the opening 102 when the operation unit 80 is arranged on the front side as shown in FIG. 4A. As shown in FIG. 4B, in the configuration in which the opening 102 is located on the front side of the apparatus and the cable 90 does not pass through the opening 102, a user may accidentally drop a part into the opening 102, and further, the appearance is bad. In case of the configuration in which the cable 90 does not pass through the opening 102, the opening 102 is placed on the back side of the apparatus instead of locating the opening 102 on the front side of the apparatus, to prevent parts from falling and to improve the appearance of the apparatus.

Similarly, the operation unit 80 not shown in FIGS. 4A and 4B is attached with the cover 101 in either a first mounting posture or a second mounting posture. Further, depending on the arranging position of the operation unit 80, the cable 90 may pass only through the opening 102 without running under the cover 101 when the cover 101 is in the second mounting posture.

(Angle of the Operation Unit)

FIG. 5A shows the operation unit 80 viewed from the above along the vertical direction, FIG. 5B shows the operation unit 80 viewed from the bottom, and FIG. 5C is a diagram showing a side view of the operation unit 80.

As shown in FIG. 5A, the operation unit 80 has the display 82. The display 82 of the operation unit 80 in this embodiment is a liquid crystal touch panel. Therefore, the display 82 can accept touch operations by a user. A touch operation is an operation of touching the display 82 with a fingertip, and is a general term for operations such as flicking and scrolling. The cable 90 extends from the back side of the operation unit 80.

Further, as shown in FIG. 5B, the bottom surface of the operation unit 80 is provided with the rubber feet 85 (85a, 85b1), which are examples of elastic members. The rubber feet 85 (85a, 85b1) are portions (feet portions) that come into contact with the top surface 109 when the operation unit 80 is arranged on the top surface 109. The rubber feet 85 are made from an elastic member having a surface with a high coefficient of friction. In this embodiment, the front side rubber feet 85a are provided at two locations on the front side and the back side rubber feet 85b1 are provided at two locations on the backside. Therefore, rubber feet are provided at four locations in total.

As shown in FIG. 5C, when the operation unit 80 is arranged on the top surface 109 which is a placement surface, the surface formed by the rubber feet 85 follows on the top surface 109 is referred to as the rubber feet surface B. The operation unit 80 is a rigid body. Therefore, if the feet portions are also rigid bodies, three of the four feet portions form a flat surface in view of tolerance. Therefore, in the case of four feet portions, when at least two of the feet portions are made of elastic bodies, the feet portions follow the surface on which the feet portions are provided. As a result, a user can stably operate the operation unit 80 on the top surface 109.

The display 82 has the display surface 820 on which information can be displayed which is related to image formation, such as a button for starting copying, a paper size

setting screen, a printed sheet count setting screen, a toner remaining amount display screen, and so on. The display surface 820 of the display 82 is the panel surface C for forming an angle of the display 82. In the present embodiment, the display surface 820 is provided on the portion of the display 82 excluding the end portion, but information regarding image formation and screens for print settings may be displayed on the entire surface of the display 82. However, in any case, the inclination angle of the display surface 820 with respect to the top surface 109 is the angle A formed by the vicinity of the center of the display 82 (the area corresponding to the display surface 820 in FIG. 5A) with respect to the top surface 109. In other words, the angle A formed by the operation unit 80 is the angle formed by the rubber foot surface B (the top surface 109) and the panel surface C (display surface 820).

The display 82 has a push range in the front and rear directions. As shown in FIG. 5C, a user operates the display 82 vertically. Therefore, the pressing force F1a on the front side of the apparatus, the pressing force F1b on the back side of the apparatus, the apparatus front side push direction line K1a, which extends to the rubber feet 85 in the direction of the pressing force F1a, and the apparatus back side push direction line K1b, which extends to the rubber feet 85 in the direction of the pressing force F1b are assumed. Further, the front side end portion of the front side rubber feet 85a is referred to as the front side rubber end portion P and the rear side end portion of the rear side rubber feet 85b1 is referred to as the back side rubber end portion M1. At this time, the front side rubber end portion P and the back side rubber end portion M1 are arranged so that the apparatus front side push direction line K1a and the apparatus back side push direction line K1b are arranged between the front side rubber end portion P and the back side rubber end portion M1.

As a result, even if the display 82 is pressed, the operation unit 80 does not rotate around the front side rubber end portion P or the back side rubber end portion M1, and the back side rubber feet 85b1 or the front side rubber feet 85a are not lifted, thereby preventing deterioration of operability.

Further, when the front side rubber end portion P of the operation unit is used as a reference, the back side rubber end portion M1 needs to be arranged on the rear side as the angle A formed by the rubber foot surface B and the panel surface C increases. When the operation unit 80 is based on the front side, it is necessary to increase the size toward the back side. Further, when the front side rubber end portion P of the operation unit is used as a reference, the back side rubber end portion M1 needs to be arranged further to the back side as the angle A formed by the rubber foot surface B and the panel surface C increases. Therefore, the back side of the operation unit 80 needs to be large-sized with the front side being a reference. In particular, when the angle A formed by the operation unit 80 is 45 degrees or more, the enlarging ratio of the back side of the operation unit increases, which makes the operation unit 80 larger, thereby limiting installation locations.

Therefore, in the present embodiment, the upper limit of the angle A formed by the operation unit 80 is set to 45 degrees, and the angle A formed by the operation unit ranges from 0 to 45 degrees. More preferably, the angle A formed by the operation unit 80 is set in the range of 5 to 45 degrees. This ensures good operability without increasing the size of the operation unit.

(Change of Angle of Operation Unit)

Users of various heights touch and operate the operation unit 80. When the height from the floor of the top surface 109 of the image forming apparatus 2 on which the operation

unit 80 is placed is limited to a predetermined height (1040 mm), the optimal angle A of the operation unit 80 is obtained as 30 degrees by calculation based on heights of users. However, there are cases where a user who is taller than the expected height or a user who is shorter than the expected height may operate the operation unit 80. Further, some users may prefer an angle A even smaller or larger than 30 degrees.

For such users, the operation unit 80 in this embodiment is configured to adjust the angle A of the operation unit 80 not only to 30 degrees, but also to an angle smaller than 30 degrees (for example, 15 degrees). Such configuration will be described next.

In this embodiment, the angle adjustment mechanism described below is configured such that the panel surface C of the display 82 of the operation unit 80 forms a first angle (15 degrees) or a second angle (30 degrees) greater than the first angle in the range of 0 to 45 degrees to the rubber foot surface B.

Although this embodiment is configured such that the angle A of the operation unit 80 can be adjusted to two different angles, the invention is not limited to this configuration and the angle A can be adjusted to three or more different angles if necessary. Although the first angle is set to 15 degrees and the second angle is set to 30 degrees, but the invention is not limited to these values and the first angle and the second angle can be appropriately set to various values.

Next, the adjustment mechanism for the angle A formed by the operation unit 80 (referred to as the angle adjustment mechanism) will be described using FIGS. 6 to 14.

First, the configuration of the angle adjustment mechanism of the operation unit 80 will be described. FIG. 6A is a perspective view of the bottom side of the operation unit 80, FIG. 6B is a perspective view of the leg portion 86 of the operation unit 80, FIG. 7A is a back side view of the leg portion 86, FIG. 7B is a perspective view of the operation unit 80 viewed from bottom surface side with the leg portion 86 being removed.

As the angle adjustment mechanism, the operation unit 80 includes the leg portion 86, the bearing 88a, the protruding portion 88b, the restricting portion 88c, and so on.

The leg portion 86 is rotatably provided on the operation unit 80. The leg portion (support portion) 86 abuts on the top surface 109 and supports the operation unit 80 such that the panel surface C of the display 82 forms a first angle or a second angle larger than the first angle with respect to the top surface 109 (rubber feet surface B) of the image forming apparatus, which is a placement surface.

FIG. 8A is a side view of the operation unit 80 with the leg portion 86 being closed. This figure shows the operation unit 80 with the leg portion 86 being rotated to the first angle (angle value A is 15 degrees). FIG. 8B is a side view of the operation unit 80 with the leg portion 86 being opened. This figure shows the operation unit 80 with the leg portion 86 being rotated to the second angle (the value of the angle A is 30 degrees).

FIG. 9A is a diagram showing a perspective view of the bottom surface side of the operation unit 80 with the leg portion 86 being closed. FIG. 9B is a diagram showing a perspective view of the bottom surface side of the operation unit 80 in an intermediate state between the closed state and the open state of the leg portion 86. FIG. 9C is a diagram showing a perspective view of the bottom surface side of the operation unit 80 with the leg portion 86 being opened. FIG. 10A is a cross-sectional view along A-A of FIG. 9A, FIG.

11

10B is a cross-sectional view along B-B of FIG. 9B, and FIG. 10C is a cross-sectional view along C-C of FIG. 9C.

As shown in FIGS. 6B and 7A, the leg portion 86 has the shaft (shaft portion) 86a which serves as a rotation center, and the mounting portion 86e provided such that the shaft 86a protrudes in the axial directions (left-right directions). The shaft 86a is provided on the mounting surface 86f of the mounting portion 86e so as to protrude in the axial direction. The mounting portion 86e is elastically deformable. Since the mounting portion 86e has the slit 86d on the side opposite to the side on which the shaft 86a is provided in the axial direction, the mounting portion 86e can be deflected in the axial direction (horizontal direction) of the shaft 86a. Further, in FIG. 6B, the mounting portion 86e has a plate-like configuration in which the length h1 in the axial directions (left-right directions) is shorter than the length h2 in the vertical direction perpendicular to the axial direction (left-right directions) ($h1 < h2$). Therefore, the mounting portion 86e can be deflected in the axial direction (left-right directions) of the shaft 86a. As will be described later, the mounting portion 86e is elastically deformable in the axial directions (left-right directions) of the shaft 86a by applying an overload exceeding a predetermined load.

The mounting portion 86e has the abutting portion 86c that abuts on the restricting portion 88c of the operation unit 80 at the position of the second angle (the position shown in FIG. 8B). When the leg portion 86 is rotated in the first direction toward the second angle from the first angle, the abutting portion 86c abuts the restricting portion 88c, so that the leg portion 86 is restricted to take the second angle. As a result, the operation unit 80 is held at the position shown in FIG. 8B.

Here, the first direction is the direction indicated by the arrow w1 shown in FIG. 10B. The first direction is the direction of rotation in which the leg portion 86 is rotated from the position of the angle shown in FIG. 10A to the position of the second angle shown in FIG. 10C. The second direction is the direction of rotation opposite to the first direction, and is the direction indicated by the arrow w2 shown in FIG. 10B. The second direction is the direction of rotation in which the leg portion 86 is rotated from the position of the second angle shown in FIG. 10C toward the position of the first angle shown in FIG. 10A.

The leg portion 86 has the protruding portion 86b that abuts on the bearing (bearing portion) 88a, which will be described later. The protruding portion 86b is provided on the mounting surface 86f of the mounting portion 86e such that the protruding portion 86b protrudes in the same direction as the shaft 86a.

As shown in FIG. 7A, in the axial directions (left-right directions), the length of the protruding portion 86b from the mounting surface 86f to the tip is shorter than the length of the shaft 86a supported by the bearing 88a. In other words, in the axial direction, the protruding length of the protruding portion 86b is shorter than the length of the shaft 86a supported by the bearing 88a.

In addition, the leg portion 86 has the rubber feet 85b1 and the rubber feet 85c. The rubber feet 85c contact the top surface 109 together with the rubber feet 85a to form the rubber feet surfaces B at the position where the operation unit 80 makes the first angle shown in FIG. 8A. The rubber feet 85b1 contact the top surface 109 together with the rubber feet 85a to form the rubber feet surfaces B at the position where the operation unit 80 makes the second angle shown in FIG. 8B.

Although the configuration in which the rubber feet 85c are provided on the leg portion 86 is illustrated, the inven-

12

tion is not limited to this configuration. The rubber feet 85c can be provided on the side of the operation unit 80 and are configured such that the rubber feet 85c contact the top surface 109 together with the rubber feet 85a to form the rubber feet surfaces B at the position where the operation unit 80 makes the first angle shown in FIG. 8A.

This embodiment shows the configuration with four rubber feet 85 which contact the top 109 of the image forming apparatus when the operation unit 80 is placed on it, but the invention is not limited to this configuration. For example, the configuration may be adopted to have two rubber feet 85 by connecting the two rubber feet 85b1 and the two rubber feet 85c to each other, respectively.

In this way, the leg portion 86 is provided with the rubber feet 85b1, the rubber feet 85c, the shaft 86a, the protruding portion 86b, the abutting portion 86c, the slit 86d, and the mounting portion 86e. In FIG. 6B, only the configuration of one direction side of the leg portion 86 in the left-right directions (right direction R) is illustrated, and the opposite side (other side in the left-right directions (left direction L)) is not shown in the figure. However, as shown in FIG. 7A, the other direction side of leg portion 86 in the left-right directions (left direction L) also has the rubber foot 85b1, the rubber foot 85c, the shaft 86a, the protruding portion 86b, the abutting portion 86c, the slit 86d, the mounting portion 86e are provided symmetrically.

As shown in FIG. 7B, the operation unit 80 has the bearing (bearing portion) 88a, the protruding portion 88b, the restricting portion 88c, the guide portion 88d, and the contact portion 88e.

The bearing 88a as the bearing portion rotatably supports the shaft 86a of the leg portion 86. The bearing 88a has the second slope 88a1, the horizontal surface 88a2, and the first slope 88a3 as shown in FIG. 12A. As will be described below, the bearing 88a is positioned such that the protruding portion 86b contacts either the slope 88a1, the horizontal surface 88a2, or the slope 88a3 of the bearing 88a as the leg portion 86 rotates, as shown in FIGS. 11A through 11C.

The horizontal surface 88a2 is provided at a position between the position of the first angle and the position of the second angle and where the horizontal surface 88a2 abuts on the protruding portion 86b of the leg portion 86. The horizontal surface 88a2 abuts on the protruding portion 86b and elastically deforms the mounting portion 86e toward the direction opposite to that in which the protruding portion 86b protrudes, and continues to maintain this elastic deformation.

The first slope 88a3 is provided at a position between the horizontal surface 88a2 and the position of the second angle and where the first slope 88a3 contacts the protruding portion 86b. The first slope 88a3 restores the elastically deformed mounting portion 86e in the direction in which the protruding portion 86b protrudes from the horizontal surface 88a2 to the position of the second angle. The first slope 88a3 is inclined forward from the front end of the horizontal surface 88a2 in the forward-backward directions.

The second slope 88a1 is provided at a position between the horizontal surface 88a2 and the position of the first angle and where the second slope 88a1 contacts the protruding portion 86b. The second slope 88a1 restores the elastically deformed mounting portion 86e in the direction in which the protruding portion 86b protrudes from the horizontal surface 88a2 to the position of the first angle. The second slope 88a1 is inclined backward from the back end of the horizontal surface 88a2 in the forward-backward directions.

The protruding portion 88b abuts the rubber foot 85 of the leg portion 86 rotated to the position with the first angle b1

and restricts the leg portion 86 in the position with the first angle. When the leg portion 86 is closed as shown in FIG. 10A, the rubber foot 85b1 of the leg portion 86 abuts on the protruding portion 88b. Therefore, this configuration not only restricts the position of the leg portion, but also muffles the sound of the abutting.

When the leg portion 86 is rotated in the first direction from the first angle to the second angle, the restricting portion 88c abuts the abutting portion 86c of the mounting portion 86e at the position where the operation unit 80 is at the second angle to restrict the rotation of the leg portion 86 in the first direction. The restricting portion 88c is provided at a different position from the bearing 88a in the axial directions (left-right directions) of the shaft 86a. The restricting portion 88c is provided more inward than the bearing 88a in the axial directions, as shown in FIGS. 12A through 12C.

The abutting portion 88e abuts on the shaft 86a. The abutting portion 88e is provided on the opposite side of the bearing 88a from the restricting portion 88c in the axial direction (left-right directions) through the bearing 88a. The abutting portion 88e is located more outward than the bearing 88a in the axial directions, as shown in FIGS. 12A through 12C.

As shown in FIGS. 7B and 12A, the guide portion 88d is provided on the side surface of the restricting portion 88c which protrudes from the operation unit 80. The guide portion 88d guides the mounting portion 86e, which is released from the abutting with the restricting portion 88c by the rotational force in the first direction against the leg portion 86 at the position with the second angle, to the position where the mounting portion 86e can be restricted by the restricting portion 88c.

The guide portion 88d is shaped to abut the mounting portion 86e and elastically deform the mounting portion 86e in the direction opposite to the direction in which the shaft 86a protrudes in the axial directions when the leg portion 86 is rotated in the second direction, opposite to the first direction. Furthermore, the guide portion 88d is shaped to release the abutting and to restore the mounting portion 86e to a position where the mounting portion 86e can be restricted by the regulating portion 88c.

Thus, the operation unit 80 has the bearing 88a, the protruding portion 88b, the restricting portion 88c, the guide portion 88d, and the abutting portion 88e. In FIG. 7B, only the configuration of one side (right direction R) of the operation unit 80 in the left-right directions is illustrated, while the opposite side (the other side (left direction L)) in the left-right directions is not shown. However, on the other side (left direction L) of the operation unit 80, the bearing 88a, the protruding portion 88b, the restricting portion 88c, the guide portion 88d, and the abutting portion 88e are also provided in a symmetrical manner.

FIG. 6A shows the operation unit 80 with the leg portion 86 being attached to the operation unit 80. The attachment of the leg portion 86 is performed by inserting the shaft 86a of the leg portion 86 shown in FIG. 6B into the bearing 88a shown in FIG. 7B. When inserting the shaft 86a into the bearing 88a, the mounting portion 86e provided with the shaft 86a is deflected using the slit 86d of the leg portion 86 shown in FIG. 7A.

As described with reference to FIGS. 6A to 7B, the leg portion 86 is attached to the operation unit 80 via the shaft 86a. Therefore, the leg portion 86 can be opened and closed around the shaft 86a as shown in FIGS. 8A and 8B. Also, when the leg portion 86 is closed as shown in FIGS. 8A and 10A, the rubber foot 85b1 butts against the protruding

portion 88b, and when the leg portion 86 is opened as shown in FIGS. 8C and 10C, the abutting portion 86c butts against the restricting portion 88c. As a result, the angle of the leg portion 86 is restricted to the position shown in FIG. 10A and to the position shown in FIG. 10C. Therefore, as shown in FIGS. 8A and 8B, the angle A of the operation unit can be adjusted in two stages: a first angle (15 degrees) when the leg portion 86 is closed and a second angle (30 degrees) when the leg portion 86 is opened.

As described above, the rubber foot 85b1 abuts on the protruding portion 88b when the leg portion 86 is closed as shown in FIG. 10A not only to restrict the position, but also to muffle the sound of the abutting.

Next, the drawing force when switching the leg portion 86 between the position of the first angle and the position of the second angle will be described. FIGS. 11A to 11C are drawings showing cross-sectional views of the vicinity of the shaft 86a of the leg portion 86 as viewed from the bottom surface side of the operation unit 80. FIG. 11A is a drawing showing a cross-sectional view of a state in which the leg portion 86 is closed, and is a cross-sectional view taken along line D-D in FIG. 10A. FIG. 11B is a drawing showing a cross-sectional view of an intermediate state between the state in which the leg portion 86 is closed and the state in which the leg portion 86 is opened, and is a cross-sectional view taken along line E-E in FIG. 10B. FIG. 11C is a drawing showing a cross-sectional view of a state in which the leg portion 86 is opened, and is a cross-sectional view taken along line F-F in FIG. 10C.

The arrows F, B, L, and R shown in FIGS. 11A to 11C indicate directions when the operation unit 80 is placed on the top surface 109 of the image forming apparatus. As described above, the direction to the front side of the image forming apparatus 2 is the forward direction F, the direction to the back (rear) side is the backward direction B, the direction to the left side is the left direction L, and the direction to the right side is the right direction R. As shown in FIGS. 11A to 11C, the protruding portion 86b of the leg portion 86 abuts on any one of the slope 88a1, the horizontal surface 88a2, and the slope 88a3 of the bearing 88a depending on whether the leg portion 86 is opened or closed.

As shown in FIG. 11B, when the leg portion 86 is in the intermediate state, neither closed nor open, the protruding portion 86b of leg portion 86 abuts the horizontal surface 88a2. Therefore, the mounting portion 86e is deflected in the left direction L, which is the direction opposite to the direction in which the shaft 86a protrudes, and a restoring force acts in the right direction R, so that the horizontal surface pushing force Fb is generated, with which the protruding portion 86b presses the horizontal surface 88a2. Since the horizontal surface pressing force Fb acts in a direction orthogonal to the horizontal surface 88a2, no sliding force in the forward direction F or the backward direction B is generated on the protruding portion 86b. Therefore, no drawing force is generated while the protruding portion 86b abuts on the horizontal surface 88a2.

Further, as described above, in the axial direction (horizontal direction), the length from the mounting surface 86f to the tip of the protruding portion 86b is shorter than the shaft 86a's length supported by the bearing 88a. Therefore, even if the protruding portion 86b abuts on the horizontal surface 88a2 of the bearing 88a and the mounting portion 86e is deflected, the shaft 86a remains supported by the bearing 88a.

The leg portion 86 having the elastically deformed mounting portion 86e is rotated in the second direction (the direction of the arrow w2 shown in FIG. 10B) toward the

position of the first angle from the horizontal plane **88a2**. In other words, the leg portion **86** is rotated in the direction in which the leg portion **86** is closed. The mounting portion **86e** is deflected in the left direction L, and a restoring force in the right direction R acts. Therefore, as shown in FIG. 11A, the slope pressing force **FaR** is generated, which is a force with which the protruding portion **86b** presses the second slope **88a1** in the axial direction. Since the slope pressing force **FaR** acts on the second slope **88a1**, the protruding portion **86b** continues to slide on the second slope **88a1** by the slope direction pressing force **Fa** of the second slope **88a1** until the opening/closing angle is restricted. As a result, the force **Fa** with which the protruding portion **86b** slides on the second slope **88a1** is converted into a force closing the leg portion **86** (a rotational force in the second direction) via the shaft **86a**. Therefore, a drawing force is generated when the leg portion **86** is switched to the position of the first angle.

The leg portion **86** having the elastically deformed mounting portion **86e** is rotated in the first direction (the direction of the arrow **w1** shown in FIG. 10B) toward the position of the second angle from the horizontal plane **88a2**. In other words, the leg portion **86** is rotated in the direction in which the leg portion **86** is opened. The mounting portion **86e** is deflected in the left direction L, and a restoring force in the right direction R acts. Therefore, as shown in FIG. 11C, the slope pressing force **FcR** is generated, which is a force with which the protruding portion **86b** presses the first slope **88a3** in the axial direction. Since the slope pressing force **FcR** acts on the first slope **88a3**, the protruding portion **86b** continues to slide on the first slope **88a3** by the slope direction pressing force **Fc** of the first slope **88a3** until the opening/closing angle is restricted. As a result, the force **Fc** with which the protruding portion **86b** slides on the first slope **88a3** is converted into a force opening the leg portion **86** (a rotational force in the first direction) via the shaft **86a**. Therefore, a drawing force is generated when the leg portion **86** is switched to the position of the second angle.

(Behavior of Leg Portion when Overload is Applied to Panel Surface of Operation Unit)

Next, the behavior of the leg portion **86** when an overload is applied to the panel surface **C** of the operation unit **80** will be described. A consideration will be given to the case where an overload exceeding the predetermined load is applied to the panel surface **C** of the operation unit **80** with the leg portion **86** being open as shown in FIG. 8B. For example, as an overload, a very strong force is applied that exceeds the typical operating force of 1.5 N (predetermined load) of the display **82**. Then, the leg portion **86**, which is restricted at the position with the second angle, receives a force for opening the leg portion **86** further, which is a rotational force in the first direction (the direction indicated by the arrow **w1** of FIG. 10B). In such a case, an overload may be transmitted to the restricting portion **88c** on the side of the operation unit **80** through the abutting portion **86c** of the leg portion **86**, and the restricting portion **88c** may be damaged.

Therefore, the operation unit **80** of this embodiment assumes the above-described overload and has a function of preventing damage to the restricting portion **88c** that restricts the opening/closing angle of the leg portion **86**.

A description will be given of the behavior of preventing damage when an overload is applied to the panel surface **C** of the operation unit **80** with the leg portion **86** being open using FIGS. 12A to 12C, 13A, 13B, 14A, and 14B.

FIG. 12A is a drawing showing a perspective view around the bearing of the operation unit **80** excluding the leg portion. FIGS. 12B and 12C are drawings each of which is a cross-sectional view around the bearing of the operation

unit **80** including the leg portion **86**, and is a cross-sectional view taken along the line **G-G** in FIG. 12A. FIGS. 13A and 14A are explanatory diagrams showing the vicinity of the bearing of the operation unit **80** when the leg portion **86** is restricted to the second position. FIGS. 13B and 14B are explanatory diagrams showing the vicinity of the bearing of the operation unit **80** with the restriction of the leg portion **86** being released.

FIGS. 13A and 14A are perspective views each of which shows the restricting portion **88c** and its vicinity of the restricting portion **88c** with the leg portion **86** being open (at the position with the second angle). FIGS. 13B and 14B are perspective views each of which shows the restricting portion **88c** and its vicinity when an overload is applied to the panel surface **C** of the operation unit **80** with the leg portion **86** being open.

FIG. 8C is a drawing showing a side view of the operation unit **80** in a state in which an overload is applied to the panel surface **C** of the operation unit **80** with the leg portion **86** being opened, and the abutting portion **86c** of the leg portion **86** is disengaged from the restricting portion **88c** that restricts the opening/closing angle.

As shown in FIGS. 12B and 12C, the restricting portion **88c** of the operation unit **80** is provided at a different position from that of the bearing **88a** in the axial directions of the shaft **86a** (horizontal directions). The abutting portion **88e** is provided on the opposite side of the bearing **88a** from the restricting portion **88c** in the axial direction via the bearing **88a**. In the axial directions, the restricting portion **88c** is provided inside the bearing **88a** and the abutting portion **88e** is provided outside the bearing **88a**.

Further, as shown in FIG. 12B, in the direction crossing the axial direction, the first abutting portion **x1** of the restricting portion **88c** on which the abutting portion **86c** abuts at the position of the second angle and the second abutting portion **x2** of the abutting portion **88e** on which the shaft **86a** abuts are located such that they are opposed to each other via the abutting portion **x3** of the bearing **88a** on which the shaft **86a** contacts.

As shown in FIGS. 13A and 14A, when the leg portion **86** is opened as shown in FIG. 10C, the leg portion **86** is restricted to the position with the second angle where the abutting portion **86c** of the leg portion **86** abuts on the restricting portion **88c** that restricts the opening/closing angle. On the other hand, as shown in FIGS. 13B and 14B, when an overload is applied to the panel surface **C** of the operation unit **80** with the leg portion **86** being opened, the mounting portion **86e** of the leg portion **86** is deflected greatly in the left direction **L**.

In detail, when the leg portion **86** which is restricted to the position with the second angle shown in FIG. 10C operates as follows when an overload exceeding the predetermined load is applied to the operation unit **80**. The rotational force in the first direction due to the overload is applied to the leg portion **86** which is restricted to the position with the second angle in the direction of the arrow **w1** shown in FIG. 10C. At this time, the abutting portion **86c** of the mounting portion **86e** receives a reaction force in the downward direction **D** from the restricting portion **88c**, and the shaft **86a** also receives a force in the upward direction **U** from the abutting portion **88e**. Then, due to the reaction force in the downward direction **D** and the force in the upward direction **U** with the contact portion **x3** on which the shaft **86a** contacts being as a fulcrum, the mounting portion **86e** is deflected in the left direction **L**. In other words, the mounting portion **86e** is elastically deformed in the axial direction in the opposite direction to that in which the shaft

86a protrudes. As shown in FIG. 12C, the abutting between the restricting portion **88c** and the mounting portion **86e** is released, and the operation unit **80** is in the state shown in FIG. 8C.

In other words, when the abutting between the mounting portion **86e** and the restricting portion **88c** is released at the position with the second angle due to the rotational force to the first direction, the leg portion **86** is in the state shown in FIG. 8C. At this time, the leg portion **86** is rotated to the position where the leg portion **86** does not protrude from the operation unit **80** toward the top surface **109**.

As shown in FIG. 8C, when the abutting portion **86c** of the leg portion **86** of the operation unit **80** is disengaged from the restricting portion **88c** that restricts the opening/closing angle, the leg portion **86** does not protrude from the surface **D** formed by the front side rubber foot **85a** and the contact point **89**. In this state, even if an overload is applied to the panel surface **C**, a force is not applied to the leg portion **86**, thereby preventing damage to the restricting portion **88c** that restricts the opening/closing angle of the leg portion **86**.

When the abutting is released from the state in which the operation unit **80** is restricted to the position with the second angle, the shaft **86a**'s axial length supported by the bearing **88a** is larger than the axial length in which the restricting portion **88c** maintains the abutting on the mounting portion **86e**. As a result, even when the restriction between the abutting portion **86c** of the leg portion **86** and the restricting portion **88c** is released, the engaging amount of the shaft **86a** with the bearing **88a** does not become less than 0. This prevents the leg portion **86** from being disengaged from the operation unit **80**. Therefore, the leg portion **86** does not come off from the operation unit **80**.

Then, the leg portion **86** with the abutting portion **86c** disengaged from the restricting portion **88c** is moved back in the closing direction, the mounting portion **86e** is guided by the guide portion **88d**. As a result, the mounting portion **86e** deflects to the left direction **L** along the guide portion **88d**, and abutting portion **86c** of the leg portion **86** abuts on the restricting portion **88c** again and returns to the original state.

In this embodiment, when the abutting portion **86c** of the leg portion **86** is disengaged from the restricting portion **88c**, the leg portion **86** is not disengaged from the operation unit **80** because the engaging amount of the shaft **86a** with the bearing **88a** is not equal to nor less than 0, so that the leg portion **86** can easily return to its original state. However, the configuration may be adopted in which the engaging amount becomes less than 0 and the leg portion **86** is disengaged from the operation unit **80**.

According to this embodiment, even if a rotational force in the first direction due to an overload is applied to the leg portion **86**, the mounting portion **86e** is elastically deformed to release the abutting between the restricting portion **88c** and the mounting portion **86e**, thereby preventing the damage of the leg portion **86** and the restricting portion **88c**.

After the leg portion **86** is disengaged from the restricting portion **88c**, when the leg portion **86** is moved back to the closing direction, the leg portion is guided by the guide portion **88d**, and the abutting portion **86c** of the leg portion **86** abuts on the restricting portion **88c** again and returns to its original state.

Second Embodiment

In the first embodiment, the angle **A** of the operation unit **80** is able to be set to 15 degrees (first angle) and 30 degrees (second angle). In this embodiment the angle **A** of the

operation unit **80** is able to be set to 0 degrees (first angle) and 20 degrees (second angle).

The operation unit of this embodiment will be described with reference to FIGS. 15 and 16A to 16C. In the operation unit of this embodiment, members having functions equivalent to those of the members of the first embodiment are denoted by the same reference numerals.

FIG. 15 is a drawing showing a perspective view of the bottom surface side of the operation unit **80** with the leg portion **86** being closed. FIG. 16A is a drawing showing a side view of the operation unit **80** with the leg portion **86** being closed. FIG. 16A is a drawing showing a side view of the operation unit **80** at the position of the first angle, exemplifying 0 degrees as the first angle. FIG. 16B is a drawing showing a side view of the operation unit **80** with the leg portion **86** being opened. FIG. 16B is a drawing showing a side view of the operating unit at the position of the second angle, exemplifying 20 degrees as the second angle. FIG. 16C is a drawing showing a side view of the operation unit **80** in a state in which the abutting portion (not shown) of the leg portion **86** is disengaged from the restricting portion (not shown) that restricts the opening/closing angle.

In the first embodiment described above, the lower limit of the angle **A** of the operation unit is desirably 5 degrees. This is because a user standing near the front side of the apparatus can easily recognize the direction of the front surface of the operation unit **80**. However, if the panel surface **C** of the operation unit **80** is printed with characters or the like that supplement the functions of the operation unit **80** and the orientation of the operation unit **80** is easy to recognize, the lower limit of the angle **A** of the operation unit **80** may be 0 degrees as shown in FIGS. 15, 16A to 16C.

In the first embodiment described above, the rubber feet **85c** are provided on the leg portion **86**, whereas in this embodiment, the rubber feet **85c** are provided on the operation unit **80**.

When the angle of the operation unit (the angle formed by the display surface **820** (panel surface **C**) of the display **82** and the top surface **109** (rubber foot surface **B**) that is the placement surface) is in the range of 0 to 45 degrees, even if the first angle and the second angle are changed, the same effect as in the first embodiment described above can be obtained.

Third Embodiment

FIG. 17A is a drawing showing a perspective view of the bottom surface side of the operation unit **80**. FIG. 17B is a drawing showing a perspective view of the leg portion **86**. FIG. 17C is a drawing showing a bottom side view of the operation unit **80** with the leg portion **86** being removed. In the operation unit of this embodiment, members having functions equivalent to those of the members of the first embodiment are denoted by the same reference numerals.

In the first embodiment, a slit **86d** is provided in the leg portion **86** so that the mounting portion **86e** is deflected in order to generate a drawing force when the leg portion **86** is attached to the operation unit **80** and when the leg portion **86** is opened and closed. However, as shown in FIGS. 17A to 17C, the configuration may be adopted in which the slit **88g** is provided in the vicinity of the bearing **88a** of the operation unit **80** so that the vicinity of the bearing **88a** of the operation unit **80** is deflected in the right direction **R** (the opposing portion of the same shape is deflected to the left direction **L**).

In other words, the operation unit **80** of this embodiment has the bearing **88a**, the restricting portion **88c**, the abutting

portion **88e**, and the second mounting portion **88h** that can be elastically deformed by an overload exceeding a predetermined load.

With this configuration, when a rotational force in the first direction due to an overload is applied to the leg portion **86** that is restricted at the position of the second angle, the second mounting portion **88h** is elastically deformed in the direction in which the shaft **86a** protrudes in the axial directions. As a result, the abutting between the restricting portion **88c** and the mounting portion **88e** is released, and the same effects as in the first embodiment can be obtained.

Fourth Embodiment

In the first embodiment, the single leg portion **86** is provided. However, separated multiple leg portions **86** may be provided as shown in FIGS. 18A to 19B. In other words, the operation unit **80** of this embodiment has multiple leg portions **86** that are rotatably provided. In the operation unit of this embodiment, members having functions equivalent to those of the members of the first embodiment are denoted by the same reference numerals.

FIG. 18A is a drawing showing a perspective view of the bottom surface side of the operation unit **80** with the leg portions **86** being closed (the angle A of the operation unit is 0 degrees). FIG. 18B is a drawing showing a perspective view of the bottom surface side of the operation unit **80** in an intermediate state between the closed state and the open state of the leg portions **86**. FIG. 19A is a drawing showing a perspective view of the bottom surface side of the operation unit **80** with the leg portions **86** being opened (the angle A of the operation unit is 20 degrees). FIG. 19B is a drawing showing a perspective view of the bottom surface side of the operation unit **80** in a state where the abutting portion of the leg portions **86** is disengaged from the protruding portion that restricts the opening/closing angle.

As described above, even with the configuration in which multiple leg portions **86** are rotatably provided, the same effect as in the first embodiment described above can be obtained.

Fifth Embodiment

FIG. 20A is a drawing showing a perspective view of the leg portion **86**. FIG. 20B is a drawing showing a perspective view of the operation unit **80** with the leg portion **86** being removed as viewed from the bottom surface side. The extendable protruding portion **86g** in FIG. 20B is urged in the left direction L from the inside by a spring. When a pushing force that overcomes the urging force is generated in the right direction R, the extendable protruding portion **86g** is accommodated within the operation unit **80**. Next, the shaft **86a** of the leg portion **86** shown in FIG. 20A is inserted into the bearing **88a** shown in FIG. 20B, so that the leg portion **86** is attached to the operation unit **80**. Then, the multiple holes **86f** of the leg portion **86** are engaged with the extendable protruding portion **86g** shown in FIG. 20B, and the opening/closing angle of the leg portion **86** is restricted according to the position of the holes **86h**.

In the first embodiment, the opening/closing angle of the leg portion **86** is restricted by the leg portion **86** abutting on the protruding portion **88b** or by the abutting portion **86c** abutting on the restricting portion **88c**. However, as shown in FIGS. 20A and 20B, the configuration may be adopted in which the extendable protruding portion **86g** urged by a spring from the inside and the multiple holes **86h** to be engaged with the protruding portion **86g** are provided, and

both of the vicinity of the bearing **88a** and the leg portion **86** in the operation unit **80** are not deflected.

Even with the configuration described above, the same effect as in the first embodiment can be obtained.

While the present invention has been described with reference to exemplary embodiments, it is to be understood that the invention is not limited to the disclosed exemplary embodiments. The scope of the following claims is to be accorded the broadest interpretation so as to encompass all such modifications and equivalent structures and functions.

This application claims the benefit of Japanese Patent Application No. 2021-199860, filed Dec. 9, 2021, which is hereby incorporated by reference herein in its entirety.

What is claimed is:

1. An operation unit used for operating an image forming apparatus that forms an image on a sheet, the operation unit comprising:

a display that displays information on image formation; and

a supporting portion configured to support the operation unit such that with a display surface of the display forming a first angle with respect to a placement surface on which the operation unit is placed or a second angle that is larger than the first angle, the supporting portion abuts on the placement surface, the supporting portion being provided on the operation unit such that the supporting portion being able to rotate between the first angle and the second angle,

wherein the supporting portion includes:

a shaft portion working as a rotational center; and

a mounting portion on which the shaft portion is provided such that the shaft portion protrudes from the mounting portion, the mounting portion being configured to be able to be elastically deformed by an overload exceeding a predetermined load,

wherein the operation unit includes:

a bearing portion configured to rotatably support the shaft portion;

a restricting portion provided at a position different from that of the bearing portion in an axial direction of the shaft portion, the restricting portion being configured such that when the supporting portion is rotated in a first direction from the first angle toward the second angle, the restricting portion restricts a rotation of the supporting portion in the first direction by abutting the mounting portion at a position where the display surface forms the second angle with respect to the placement surface; and

an abutting portion provided on an opposite side of the restricting portion via the bearing portion in the axial direction, the abutting portion being configured to abut on the shaft portion, and

wherein when a rotational force in the first direction by the overload is applied to the supporting portion that is restricted to the position where the display surface forms the second angle, the mounting portion is elastically deformed in a direction opposite to a direction in which the shaft portion protrudes in the axial direction to release the abutting between the restricting portion and the mounting portion.

2. The operation unit according to claim 1,

wherein in the operation unit, a first abutting portion at which the restricting portion abuts on the mounting portion and a second abutting portion at which the abutting portion abuts on the shaft portion are opposed to each other via a contact portion between the bearing portion and the shaft portion.

21

3. The operation unit according to claim 1, wherein when the abutting between the mounting portion and the restricting portion is released at a position where the display surface forms the second angle by a rotational force in the first direction, the supporting portion is rotated to a position where the supporting portion does not protrude from the operation unit toward the placement surface.

4. The operation unit according to claim 1, wherein the operation unit has a guide portion configured to guide the mounting portion whose abutting on the restricting portion is released at a position where the display surface forms the second angle by a rotational force in the first direction to a position where restriction by the restricting portion is possible.

5. The operation unit according to claim 4, wherein the guide portion is so shaped that when the supporting portion is rotated in a second direction opposite to the first direction, the guide portion abuts on the mounting portion and elastically deforms the mounting portion in a direction opposite to the direction in which the shaft portion protrudes in the axial direction to release the abutting and to restore the mounting portion to a position where restriction of the restricting portion is possible.

6. The operation unit according to claim 1, wherein when the abutting is released from the state in which the operation unit is restricted to the position where the display surface forms the second angle, the shaft portion's axial length supported by the bearing portion is larger than the axial length in which the restricting portion maintains the abutting with the mounting portion.

7. The operation unit according to claim 1, wherein the mounting portion has a protruding portion which protrudes in the same direction as that of the shaft portion, the protruding portion being configured to abut on the bearing portion, and

wherein the bearing portion has a plane configured to abut on the protruding portion between a position where the display surface forms the first angle and a position where the display surface forms the second angle and to elastically deforms the mounting portion in a direction opposite to the direction in which the protruding portion protrudes in the axial direction, a first slope configured to restore the elastically deformed mounting portion in a direction in which the protruding portion protrudes from the plane to the position where the display surface forms the second angle, and a second slope configured to restore the elastically deformed mounting portion in a direction in which the protruding portion protrudes from the plane to the position where the display surface forms the first angle.

8. The operation unit according to claim 1, wherein the display surface of the display forms the first angle or the second angle larger than the first angle within the range of 0 to 45 degrees with respect to the placement surface on which the operation unit is placed.

9. The operation unit according to claim 1, wherein the operation unit is connected to the image forming apparatus by a cable.

10. The operation unit according to claim 1, wherein the supporting portion is rotatably provided in a plurality on the operation unit.

22

11. An operation unit used for operating an image forming apparatus that forms an image on a sheet, the operation unit comprising:

a display that displays information on image formation; and
a supporting portion configured to support the operation unit such that with a display surface of the display forming a first angle with respect to a placement surface on which the operation unit is placed or a second angle that is larger than the first angle, the supporting portion abuts on the placement surface, the supporting portion being provided on the operation unit such that the supporting portion being able to rotate between the first angle and the second angle,

wherein the supporting portion includes:

a shaft portion working as a rotational center; and
a first mounting portion on which the shaft portion is provided,

wherein the operation unit includes:

a bearing portion configured to rotatably support the shaft portion;

a restricting portion provided at a position different from that of the bearing portion in an axial direction of the shaft portion, the restricting portion being configured such that when the supporting portion is rotated in a first direction from the first angle toward the second angle, the restricting portion restricts a rotation of the supporting portion in the first direction by abutting the first mounting portion at a position where the display surface forms the second angle with respect to the placement surface;

an abutting portion provided on an opposite side of the restricting portion via the bearing portion in the axial direction, the abutting portion being configured to abut on the shaft portion; and

a second mounting portion on which the shaft portion, the restricting portion and the abutting portion are provided, the second mounting portion being configured to be able to be elastically deformed by an overload exceeding a predetermined load

wherein when a rotational force in the first direction by the overload is applied to the supporting portion that is restricted to the position where the display surface forms the second angle, the second mounting portion is elastically deformed in a direction in which the shaft portion protrudes in the axial direction to release the abutting between the restricting portion and the first mounting portion.

12. An image forming apparatus having an image forming portion that forms an image on a sheet, and an operation unit used for operating the image forming apparatus, the operation unit comprising:

a display that displays information on image formation; and

a supporting portion configured to support the operation unit such that with a display surface of the display forming a first angle with respect to a placement surface on which the operation unit is placed or a second angle that is larger than the first angle, the supporting portion abuts on the placement surface, the supporting portion being provided on the operation unit such that the supporting portion being able to rotate between the first angle and the second angle,

wherein the supporting portion includes:

a shaft portion working as a rotational center; and
a mounting portion on which the shaft portion is provided such that the shaft portion protrudes from

23

the mounting portion, the mounting portion being configured to be able to be elastically deformed by an overload exceeding a predetermined load,

wherein the operation unit includes:

- a bearing portion configured to rotatably support the shaft portion;
  - a restricting portion provided at a position different from that of the bearing portion in an axial direction of the shaft portion, the restricting portion being configured such that when the supporting portion is rotated in a first direction from the first angle toward the second angle, the restricting portion restricts a rotation of the supporting portion in the first direction by abutting the mounting portion at a position where the display surface forms the second angle with respect to the placement surface; and
  - an abutting portion provided on an opposite side of the restricting portion via the bearing portion in the axial direction, the abutting portion being configured to 20 abut on the shaft portion, and
- wherein when a rotational force in the first direction by the overload is applied to the supporting portion that is restricted to the position where the display surface forms the second angle, the mounting portion is elastically deformed in a direction opposite to a direction in which the shaft portion protrudes in the axial direction to release the abutting between the restricting portion and the mounting portion.

13. The image forming apparatus according to claim 12, wherein in the operation unit, a first abutting portion at which the restricting portion abuts on the mounting portion and a second abutting portion at which the abutting portion abuts on the shaft portion are opposed to each other via a contact portion between the bearing portion and the shaft portion.

14. The image forming apparatus according to claim 12, wherein when the abutting between the mounting portion and the restricting portion is released at a position where the display surface forms the second angle by a rotational force in the first direction, the supporting portion is rotated to a position where the supporting portion does not protrude from the operation unit toward the placement surface.

15. The image forming apparatus according to claim 12, wherein the operation unit has a guide portion configured to guide the mounting portion whose abutting on the restricting portion is released at a position where the display surface forms the second angle by a rotational force to the first direction to a position where restriction by the restricting portion is possible.

16. The image forming apparatus according to claim 15, wherein the guide portion is so shaped that when the supporting portion is rotated in a second direction opposite to the first direction, the guide portion abuts on the mounting portion and elastically deforms the mounting portion in a direction opposite to the direction in which the shaft portion protrudes in the axial direction to release the abutting and to restore the 60 mounting portion to a position where restriction of the restricting portion is possible.

17. The image forming apparatus according to claim 12, wherein when the abutting is released from the state in which the operation unit is restricted to the position where the display surface forms the second angle, the shaft portion's axial length supported by the bearing

24

portion is larger than the axial length in which the restricting portion maintains the abutting with the mounting portion.

18. The image forming apparatus according to claim 12, wherein the mounting portion has a protruding portion which protrudes in the same direction as that of the shaft portion, the protruding portion being configured to abut on the bearing portion, and

wherein the bearing portion has a plane configured to abut on the protruding portion between a position where the display surface forms the first angle and a position where the display surface forms the second angle and to elastically deform the mounting portion in a direction opposite to the direction in which the protruding portion protrudes in the axial direction, a first slope configured to restore the elastically deformed mounting portion in a direction in which the protruding portion protrudes from the plane to the position where the display surface forms the second angle, and a second slope configured to restore the elastically deformed mounting portion in a direction in which the protruding portion protrudes from the plane to the position where the display surface forms the first angle.

19. The image forming apparatus according to claim 12, wherein the display surface of the display forms the first angle or the second angle larger than the first angle within the range of 0 to 45 degrees with respect to the placement surface on which the operation unit is placed.

20. The image forming apparatus according to claim 12, wherein the operation unit is connected to the image forming apparatus by a cable.

21. The image forming apparatus according to claim 12, wherein the supporting portion is rotatably provided in a plurality.

22. An image forming apparatus having an image forming portion that forms an image on a sheet, and an operation unit used for operating the image forming apparatus, the operation unit comprising:

a display that displays information on image formation; and

a supporting portion configured to support the operation unit such that with a display surface of the display forming a first angle with respect to a placement surface on which the operation unit is placed or a second angle that is larger than the first angle, the supporting portion abuts on the placement surface, the supporting portion being provided on the operation unit such that the supporting portion is able to rotate between the first angle and the second angle,

wherein the supporting portion includes:

a shaft portion working as a rotational center; and a first mounting portion on which the shaft portion is provided,

wherein the operation unit includes:

a bearing portion configured to rotatably support the shaft portion;

a restricting portion provided at a position different from that of the bearing portion in an axial direction of the shaft portion, the restricting portion being configured such that when the supporting portion is rotated in a first direction from the first angle toward the second angle, the restricting portion restricts a rotation of the supporting portion in the first direction by abutting the first mounting portion at a position where the display surface forms the second angle with respect to the placement surface;

an abutting portion provided on an opposite side of the restricting portion via the bearing portion in the axial direction, the abutting portion being configured to abut on the shaft portion; and
a second mounting portion on which the shaft portion, 5 the restricting portion and the abutting portion are provided, the second mounting portion being configured to be able to be elastically deformed by an overload exceeding a predetermined load
wherein when a rotational force in the first direction by 10 the overload is applied to the supporting portion that is restricted to the position where the display surface forms the second angle, the second mounting portion is elastically deformed in a direction in which the shaft portion protrudes in the axial direction to release the 15 abutting between the restricting portion and the first mounting portion.
